CLAIM

I claim an electrosurgical device, as shown and described.

DESCRIPTION

FIG. 1 is a top perspective view of an electrosurgical device showing my new design;

FIG. 2 is a front elevational view thereof, the undisclosed rear being a mirror image;

FIG. 3 is a top plan view thereof;

FIG. 4 is a bottom plan view thereof;

FIG. 5 is a right side elevational view thereof;

FIG. 6 is a left side elevational view thereof; and,

FIG. 7 is a front elevational view thereof, shown in an alternate position.
